(57) **CLAIM**

The ornamental design for a radiator grille for a vehicle, as shown and described.

DESCRIPTION

This application contains subject matter related to the following co-pending U.S. design patent application:

Application Ser. No. 29/572,848, filed herewith and entitled “Truck Cab, Toy, and/or Replicas Thereof”.

FIG. 1 is a left, front perspective view of a radiator grille for a vehicle according to the design, the right, front perspective view being a mirror image thereof;

FIG. 2 is a front view thereof;

FIG. 3 is a top view thereof;

FIG. 4 is a left side view thereof;

FIG. 5 is a right side view thereof; and,

FIG. 6 is a rear view thereof.

The broken lines represent unclaimed subject matter and form no part of the claimed design.

1 Claim, 5 Drawing Sheets
